UNITED STATES PATENT OFFICE.

FREDERICK MAYER, OF BALTIMORE, MARYLAND.

APPARATUS FOR MANUFACTURE OF OIL-GAS.

SPECIFICATION forming part of Letters Patent No. 542,269, dated July 9, 1895.

Application filed December 11, 1894. Serial No. 531,511. (No model.)

To all whom it may concern:

Be it known that I, FREDERICK MAYER, of the city of Baltimore, in the State of Maryland, have invented certain Improvements in 5 Apparatus for the Manufacture of Oil-Gas, of which the following is a specification.

This invention relates to the carbureting of water-gas or the enriching of illuminating-gas of a low illuminating power, as will hereinafter fully appear.

In the description of the said invention which follows reference is made to the accompanying drawings, forming a part hereof, and in which—

15 Figure 1 is an exterior side view of the apparatus. Fig. 2 is an exterior front view. Fig. 3 is a central section of Fig. 2, taken on the dotted line xx . Fig. 4 is a section of Fig. 1, taken on the dotted line yy . Fig. 5 is a 20 section of Fig. 1, taken on the dotted line zz . Fig. 6 is an exterior plan of the apparatus. Fig. 7 is a sectional plan taken on the dotted line $x'x'$. Fig. 8 is a sectional plan taken on the dotted line $y'y'$. Fig. 9 is a sectional 25 plan taken on the dotted line $z'z'$. Fig. 10 is a sectional plan taken on the dotted line x^2x^2 . Figs. 11 to 15, inclusive, are enlarged details hereinafter described.

Referring now to the drawings, A is the 30 brickwork-casing of the apparatus, strengthened and supported by the iron sheathing a .

B is the furnace, and b the grate-bars in the furnace.

C is a brickwork arch situated over the furnace, having openings c for the passage of carbonic oxide. Immediately above this arch the carbonic oxide meets with a secondary supply of air and the products of combustion ascend to the retort-chamber hereinafter referred to.

40 D are vertical retorts situated in the retort-chamber E. These retorts project through the brickwork A and have suitable lids d hinged to levers e , whereby the lids are held 45 tightly in place. The lower ends of the retorts are turned outward at a right angle, and closed by means of lids g , similar to those d , before referred to. The horizontal portion f of each retort has a take-off pipe h , of ordinary construction, leading to a hydraulic main j , of well-known character.

Six retorts are shown in the retort-chamber,

and they are grouped together so as to occupy, with their connections, the entire chamber.

The retorts D are made in, say, three 55 lengths, and the two lower lengths have each three wings k , which are cut away at certain points to form spaces l for the passage of the products of combustion from the furnace. (See, particularly, Figs. 3, 4, and 7.) Between 60 the two rows of retorts are plates m , of such character, size, and shape that when connected or placed in position around the retorts there are left between them spaces n and o , the former being rectangular and the latter circular, 65 as seen from either the top or bottom. The last-named spaces n and o are for the upward passage of the products of combustion and the ones l for the downward passage of the same.

70 From the foregoing description it will be seen that the retorts are entirely enveloped by the hot products of combustion from the furnace, the heat ascending through the space between the two rows of retorts and descending through the spaces b^2 between the retorts and the outer wall of the brickwork casing A.

75 Some of the ascending products escape laterally from the central spaces n and o to the spaces b^2 , between the retorts and brickwork, 80 through the openings l ; but this movement of a portion of the products does not interfere with their general direction, as described.

85 Notwithstanding the length of the retorts and the direction of the currents of the products of combustion, as specified, the hottest products will collect at the highest point. Consequently the upper ends of the retorts are hotter, or, rather, receive more heat, than the lower ones.

90 From the foregoing statement it must not be understood that the upper ends of the retorts, while the apparatus is in operation, are maintained at a much higher temperature than the remaining portions, as the excess of 95 heat imparted to them is transmitted to or carried off by the hydrocarbon vapor, which is admitted to the retorts in a comparatively cool condition, as hereinafter more particularly described.

100 Referring now particularly to Figs. 3 and 10, it will be seen that in the brickwork in the rear of the furnace are formed primary airducts p , which have branches q leading rear-

ward to a space r and then forward to a second space s , from which lead the ducts t , having branches u , which terminate at the ash-pit below the grate-bars.

5 The direction taken by the primary air-currents, which effect the generation of carbonic oxide in the furnace, is well shown by the arrows.

The movement of or the direction taken by 10 the various gases, together with the products of combustion and the primary and secondary air, is designated by the various arrows shown on Sheet 4.

In connection with the primary air-ducts 15 just described are the secondary air-ducts. (Shown particularly in Figs. 3 and 10.) The secondary air enters at a' , passes rearward along the ducts b' to the space c' , thence returning in a forward direction through the 20 ducts d' , then rises through the duct h^2 , from which it passes into chamber d^4 , thence to the channel f^4 to the ducts f' , which terminate immediately above the openings c in the arch C . By this means the secondary air, the 25 course of which is shown by arrows, combines with the carbonic oxide issuing from the furnace and effects complete combustion, the resultant products passing upward and returning downward, as before described. The said 30 products now pass into the flues c^2 , from which they finally escape to the regenerator through branch flues d^2 . The flues d^2 are in communication with a chamber f^2 , from which the flues g^2 lead to a second chamber h^5 . (Shown 35 in dotted lines.) From this second chamber h^5 extend other flues j^2 in communication with a third chamber k^2 . From the lower end of this third chamber k^2 lead flues m^2 , extending to side channels n^2 , which have openings 40 o^2 , leading to a flue o^4 in communication with the oil-vaporizing chamber A^2 . Within the oil-vaporizing chamber are partitions p^2 , arranged so that each alternate one projects 45 from the partition-wall H and stops short of the rear wall q^2 , and the intermediate ones extend from the rear wall toward, but stop short of, the partition-wall H . By this arrangement a circuitous passage is formed for the ascent 50 of the products of combustion through the chamber. The products of combustion on leaving the flue o^4 enter the lowest one of the spaces r^2 , formed by the partitions p^2 , and pass through the circuitous passage described, finally escaping into the stack B^2 .

55 C^2 and C^2 are pipes extending transversely through the oil-vaporizing chamber A^2 , into which oil, or rather some hydrocarbon, is introduced to be vaporized. These pipes are arranged in gangs, and each gang extends 60 from the top to the bottom of the chamber A^2 . The pipes of each gang are inclined, so that the oil and vapor have a regular descent, and they are connected together at the ends, exteriorly of the brickwork, by suitable fittings, 65 short pipes, and unions, as shown particularly in Figs. 1 and 5. The object in extending the vaporizing-pipes to the outside of the

brickwork is to admit of the pipes being readily cleaned and repaired.

The portions of the gang-pipes and their 70 connections which project from the brick-work A are covered by sheet-iron boxes C^3 , fastened to the iron sheathing a , to retard radiation of heat. An enlarged view of a portion of one of these boxes is shown in Fig. 15. 75

Fig. 5 shows one complete gang of vaporizing-pipes in full lines. These pipes C^2 are covered where they pass through the chamber A^2 , so that they will not be injured by contact with the products of combustion, and 80 also that the heat imparted to them may be retained. All the gang-pipes terminate in a manifold D^2 , which is in communication with a pipe E^2 by means of a branch pipe F^2 , built in the partition-wall H . The upper end of 85 the pipe E^2 is united with a manifold G^2 , having branch pipes H^2 , leading to the retorts D . The oil-vapor is therefore introduced into the retorts at their upper and hottest ends.

Referring now particularly to Figs. 11, 12, 90 13, and 14, which illustrate, on an enlarged scale, the apparatus which is used to introduce the hydrocarbon to the vaporizing-pipes C^2 , J^2 is a box into the lower side of which the oil-vaporizing pipes C^2 enter.

95 K^2 is a hydrocarbon-supply pipe suspended within the box J^2 by means of bolts a^3 , having cross-heads b^3 at the outer ends, which are supported by other bolts d^3 , which project from the upper side of the box J^2 . The central bolts a^3 pass through stuffing-boxes e^3 , to prevent escape of gas, and the bolts d^3 have lock-nuts f^3 , whereby the length of projection of the central bolt a^3 within the box may be adjusted. The object in supporting the pipe 100 K^2 as described is to allow of the said pipe being leveled within the box.

105 M^2 is a pipe leading from a suitable tank containing hydrocarbon, (not shown,) having a branch g^3 , which passes through a stuffing-box h^3 and enters the supply-pipe K . Between the pipe M^2 and the branch g^3 is a valve i^3 of any appropriate construction, for regulating the flow of the hydrocarbon to the supply-pipe K^2 .

110 In the top of the supply-pipe K^2 are slots j^3 , through which the hydrocarbon overflows to the outside of the said pipe, and at the bottom of the said pipe are knife-edged angular plates k^3 , one of which is situated directly over each pipe C^2 . The oil in its overflow trickles down to the knife-edged plates, and from their points drops into the vaporizing-pipes C^2 ; thence passes down the several 115 gangs of vaporizing-pipes, as before described, in the form of vapor to the retorts, where, being subjected to an intense heat, it is changed into a fixed gas, which is ultimately 120 discharged into the hydraulic main j , where it is mixed with water-gas, or any other gas 125 of low illuminating power, introduced into the hydraulic main through the pipes a^4 , which lead in the present case from a water-gas generator. (Not shown.)

The carbureted gas is drawn from the hydraulic main through the pipe A⁴.

From the foregoing description it will be understood that the greatest heat in the vaporizing-chamber is at the bottom. Consequently the upper ends of the vaporizing-pipes are cooler than the lower ones. By introducing the hydrocarbon into the coolest end of the pipes the vaporizing operation is at first slow, and gradually increases as the oil and vapor descend until it is fully accomplished before passing into the retorts.

The introduction of the hydrocarbon-vapor to the retorts has a tendency to cool the ends of the retorts first receiving them, and, indeed, in horizontally-placed retorts, this cooling effect is so considerable as to render, in some cases, about one-third of their length inoperative for the purpose; but in vertical retorts arranged as described—that is to say, so that their upper ends, which are subjected to the cooling influence of the vapor, receive the greatest heat, and therefore the cooling tendency of the vapor is neutralized, and the whole length of the retorts becomes effective in the operation of changing the hydrocarbon-vapor into a fixed gas.

In case oil, instead of coke or coal, is to be used as a fuel the oil is injected through a pipe a⁵ by means of a blast introduced through the pipes b⁵, and the openings c in the arch C over the furnace are closed with fire-brick.

Instead of introducing the water-gas into the hydraulic main, as described, it may be passed directly into the box J² through a pipe J³, and in such a case the water-gas will traverse the vaporizing-pipes in connection with the hydrocarbon-vapor, and finally both will enter the upper ends of the retorts, from the bottom of which the carbureted gas is drawn to the hydraulic main.

I claim as my invention—

1. In an apparatus for carbureting water gas, the combination of a retort chamber containing a series of vertical retorts, a furnace situated under the retort chamber and separated from it by a perforated arch, a body of brickwork in the rear of the furnace having circuitous passages therein through which the products of combustion from the retort chamber pass to heat it, a vaporizing chamber erected over the said brickwork having

circuitous passages therein, which form a continuation of those in the said brickwork, and which lead finally to a stack, gaugs of vaporizing pipe which are partially or wholly within the said vaporizing chamber, leading ultimately to the upper ends of the retorts, to convey hydro-carbon vapors from the top of the vaporizing chamber to the top of the retorts, substantially as specified. 55

2. In an apparatus for carbureting water gas, a furnace covered by a perforated arch, combined with a retort chamber erected over the said arch, a system of vertical retorts situated in the said retort chamber, having wings which are cut away at certain points to give continuity to the various spaces exterior of the retorts and between them and the brick-work of the retort chamber, and plates which form partitions in the retort chamber between the rows of retorts therein, provided with spaces or openings through which the products of combustion ascend to the upper portion of the retort chamber, substantially as specified. 60 70 75

3. In an apparatus for carbureting water gas, the combination of a vaporizing chamber and a series of vaporizing pipes within the said chamber with their ends projecting from it, a box to which the ends of the said vaporizing pipes are connected, a supply pipe supported within the said box having knife-edged, or conducting plates, the points of which are over the ends of the said pipes, and overflow apertures, and a pipe for conveying hydrocarbon to the said supply pipe, substantially as specified. 80

4. In an apparatus for carbureting water gas, the combination of a series of vaporizing pipes connected to a box at their ends, a supply pipe in the said box having knife-edged triangular plates on its lower side with the points over the ends of the said vaporizing pipes, a conveying pipe to feed the supply pipe, and sustaining bolts which pass through stuffing boxes in the top of the said box and are adjustable in length whereby the said supply pipe may be leveled in the said box 100 without reference to its position, substantially as specified. 90 95

FREDERICK MAYER.
